UNITED STATES PATENT OFFICE

172,686

GOLF GAME BOARD

Walter J. Rittle, Lebanon, Pa.

Application April 7, 1953, Serial No. 24,388

Term of patent 14 years

(Cl. D34—5)

To all whom it may concern:

Be it known that I, Walter J. Rittle, a citizen of the United States of America, residing at Lebanon, in the county of Lebanon and Commonwealth of Pennsylvania, have invented a new, original, and ornamental Design for a Golf Game Board, of which the following is a specification, reference being had to the accompanying drawings, forming part thereof.

Fig. 2 is an edge view thereof.

Fig. 3 is a partial bottom view of Fig. 1.

I claim:

The ornamental design for a golf game board, as shown.
